TYPEWRITER DESK

William James Bargen, Waukegan, Ill.

Application January 7, 1943, Serial No. 471,592

5 Claims. (Cl. 312—29)

This invention relates to typewriter desks.

An object of this invention is to provide a desk of simple construction which is adapted to house a typewriter in concealed position.

A further object of this invention is to provide in a desk of this type an improved typewriter base board and correlated means carried by the desk and base board for holding the board in adjusted operative position.

A further object of this invention is to provide in a desk of this type an improved typewriter base board which is provided with rollers to facilitate movement of the latter, the desk being provided with a track over which the rollers are adapted to engage.

A further object of this invention is to provide in a desk of this type an improved bumper or stop for the typewriter base board against which the base board is adapted to engage when the latter is in the storage compartment.

A further object of this invention is to provide a desk having a storage compartment for a typewriter or other machine, the desk being so constructed that when the typewriter is in the storage compartment the front portion of the top may be raised to permit the placement of a comptometer or the like on the horizontal shelf.

A further object of this invention is to provide a desk having a hinged top and a storage compartment with a shelf at the forward portion of the desk beneath the top, the upper front portion of the desk being open so that when the top is in closed position various articles such as books, papers or the like may be placed on the shelf.

A further object of this invention is to provide a desk of this type having a top formed of two sections hinged together and one of the sections hinged to the body of the desk, the latter section including opposite side rails, and a rear rail for preventing papers and the like from sliding off of the top when the latter is raised or when the front section is raised, the front ends of the side rails being upwardly and rearwardly inclined and forming stops for holding the front section in raised position.

A further object of this invention is to provide a desk including a body having a forwardly offset upper portion which serves as a means for providing increased leg space beneath the desk, thereby permitting the operator to turn in a chair without pushing the chair rearwardly.

A further object of this invention is to provide a desk of this type embodying a sectional hinged top, the front section of the top constituting a copy holder when in raised position.

To the foregoing objects and others which may hereinafter appear, the invention consists of the novel construction, combination and arrangement of parts as will be more specifically referred to and illustrated in the accompanying drawings.

but it is to be understood that changes, variations and modifications may be resorted to which fall within the scope of the invention as claimed.

In the drawings:

5 Figure 1 is a detail side elevation of a typewriter desk constructed according to an embodiment of this invention;

Figure 2 is a plan view of the desk;

10 Figure 3 is a sectional view taken on the line 3—3 of Figure 2, with the front portion of the top in open position;

Figure 4 is a plan view, partly broken away, of the desk with the top removed;

15 Figure 5 is a sectional view taken on the line 5—5 of Figure 3;

Figure 6 is a fragmentary vertical sectional view showing the rear portion of the top in open position;

20 Figure 7 is a sectional view taken on the line 7—7 of Figure 6;

Figure 8 is a bottom plan of the typewriter base board;

25 Figure 9 is a fragmentary sectional view taken on the line 9—9 of Figure 4; and

Figure 10 is a sectional view taken on the line 10—10 of Figure 9.

Referring to the drawings the numeral 15 designates generally a hollow body or base structure which is formed of opposite side walls 16 and 17 and a rear end wall 18. The side walls 16 and 17 are of like construction and each includes vertically disposed posts or legs 19 and 20 which are connected together by upper and lower rails 21 and 22 respectively. A panel 23 is secured between the legs 19 and 20 and the rails 21 and 22. The bottom rail 22 is disposed upwardly from the lower ends of the legs 19 and 20, as shown in Figures 1 and 2, and that portion of each of the legs extending below the lower rail 22 is tapered as at 24. The back wall 18 is constructed of upper and lower rails 25 and 26 respectively which are provided with confronting grooves 27 and 28 respectively within which a back panel 29 is adapted to be positioned.

45 The opposite vertical edges of the panel 29 are extended into vertical grooves 30 which are formed in the corner posts, as shown in Figure 5.

The side walls 16 and 17 are each provided with 50 portions 31 which extend forwardly beyond the front legs 19, and a horizontal shelf 32 is secured between the extensions 31 and also between portions of the side walls 16 and 17, as shown in Figure 3. An inclined wall or partition 33 is disposed between the side walls 16 and 17, and comprises an upper rail 34 which is secured at its upper forward edge to the rear edge of the shelf or horizontal wall 32.

55 A pair of downwardly and rearwardly inclined rails 35 are secured at their upper ends to the 60

upper rail 34, and at the lower ends to a lower rail 36. The lower rail 36 is bevelled off at its lower rear edge and secured by fastening members 37 to the inner side of the lower rear rail 26. The upper and lower rails 34 and 36 are provided, at their confronting edges, with grooves 38 and 39 respectively and a panel 40 is engaged in the grooves 38 and 39 and also in similar grooves provided in the longitudinal rails 35. The rails 35 constitute tracks or guide members, the purpose for which will be hereinafter described.

The wall 33 provides a substantially triangular storage chamber 41 in the body 15, and also provides a leg space 42 outwardly and forwardly of the wall 33. The typewriter base board 43, which is shown more clearly in Figure 8, is adapted to movably engage on the wall 33 or shelf or horizontal wall 32. The base 43 comprises a rectangular body or board 44 which is provided in the opposite side edges thereof, and adjacent the forward portion, with cutouts 45. The base board 43 is of a width sufficient to loosely engage between the side walls of the body 15 and the cutouts 45 provide space on the opposite side edges of the body 44 so that the base board 43 may be extended forwardly beyond the forward edges of the extensions 31. The extensions 31 are provided on the inner sides or faces thereof with inwardly projecting vertical flanges 46 which serve as stop means to limit the forward movement of the base 43.

The horizontal wall 32, on the upper side and adjacent the forward edge thereof is provided with a pair of upwardly extending flanges 47. The base board 43 is formed in the lower side thereof with aligned pairs of grooves 48 within which the flanges 47 are adapted to engage. The grooves 48 are correlated with the flanges 47 in providing means for firmly holding the base board 43 in selected extended position on the upper side of the horizontal wall 32. The horizontal wall 32, at the opposite side edges thereof, has secured thereto, a pair of strips or track forming members 49 which constitute continuations or extensions of the inclined rails or guides 35. In order to facilitate the movement of the base board 43 to either an extended position, which is the position shown in full lines in Figure 3, or to a storage position, as shown by dotted lines in Figure 3, the base board 43 is provided adjacent each side edge thereof with pairs of rollers 50. The rollers 50 are carried by a circular plate 51 engaging in a recess 52 formed in the lower side of the body 44, and upwardly projecting tangs 53 are formed integral with the plate 51 and are driven into the board 44 from the lower side thereof. The board 44 is formed with a recess 54 in which the roller 50 is adapted to loosely engage and the roller 50 is rotatably secured to the plate 51 between a pair of upwardly projecting ears 55 struck from the plate 51, and in which the roller shaft 56 rotatably engages.

A typewriter or other instrument is adapted to be bolted or otherwise firmly secured to the upper side of the base board 43 and, if desired, one instrument may be secured to the board 43 and left in the storage chamber 41 whereas a second instrument, such as a comptometer or the like may be removably mounted on the horizontal shelf or wall 32.

The base board 43, when disposed in the storage chamber 41, is adapted to engage against a pair of rubber or resilient cushion members 57 which are carried by downwardly and forwardly inclined stop members 58. The stop mem-

bers 58 are secured by fastening members 59 to the inner sides of the rear posts or legs 20, and each stop member 58 is formed with an upwardly opening cutout 60 in which the lower portion of the base board 43 is adapted to removably engage. The upper edge of the cutout 60 is parallel with the adjacent side of the inclined wall 33 and the stop or cushion member 57 is disposed at the bottom of the cutout 60. The cutout 60 also provides a means for holding the base board 43 against rearward tilting when the board 43, with a typewriter or other instrument secured thereto, is in the storage chamber 41.

A top, generally designated as 61, is mounted on the upper side of the body 15 and comprises a rear top section 62 and a front top section 63. The rear section 62 is hingedly secured, as by hinge means 64, to the upper edge of the rear rail 25 and the two top sections 62 and 63 are hingedly secured together, as at 65. The rear top section 62 has secured to the upper side thereof an upwardly extending rail or board 66 and a pair of upwardly extending side rails or boards 67 are secured at their rear ends to the bottom rail 66. The forward ends of the side rails 67 are cut off on an angle as, at 68, and constitute stop means for limiting the swinging or pivoting of the front top section when the latter is in an open operative position, as shown in Figure 3. In this open position the front top section is inclined upwardly and to the rear and constitutes in this position, a work holder for holding work such as paper, a book or other work so that the user can see the work above the typewriter or other instrument positioned on the extended base board 43. A work holding rail 69, including an upwardly extending flange 70, is secured to the lower side of the top section 63, and the work is adapted to rest on the work holding rail 69 inside the flange 70.

The rear top section 62 is adapted to be balanced or held in an up-raised position by means of a spring-pressed balancing device, generally designated as 71. The balancing or holding device 71 includes a lever 72 which is pivotally mounted on a pivot 73 carried by a plate 74. The plate 74 is secured by fastening members 75 to the inner side of one of the upper side rails 21, and the rail 21 is also formed with a horizontal opening or slot 76 slightly smaller in width and length than the plate 74. A link 77 is pivotally secured, as at 78, to the lever 72, and the link 77 is also pivotally secured as at 79 to a downwardly extending ear 80 carried by the plate 81. The plate 81 is secured by fastening means 82 to the lower side of the rear top section 62. In order to provide a means whereby the top 62 may be held in an up-raised position, I have provided a lifting link 83 which is pivotally secured as at 84 to the lever 72 between the two pivotal members 73 and 78.

The lifting link 83 has secured thereto a pin or bolt 85 which is slidable in an elongated horizontal slot 86 formed in the plate 74. The plate 74, at its rear end, is provided with an inwardly projecting ear 87 extending into the recess 76 and one end of a contraction spring 88 is secured, as at 89, to the inwardly projecting ear 87. The opposite end of the spring 88 is secured, as at 90, to the bolt or pin 85.

In the use and operation of this desk structure, a typewriter or other office machine or instrument may be secured to the base 43 and when the instrument is not in use it may be positioned in the storage chamber 41 with the top 61 in a hori-

zontal position. In this position of the desk books, or the like may be placed on the shelf or wall 32, the front of the desk above the wall 32 and below the top section 63 being open. The top of the desk may be used in a normal manner, the U-shaped material holding rail structure embodying the rails 66 and 67 preventing any books, papers or the like from slipping off the rear or side portions of the top 61.

The typewriter may be moved to an extended operative position by pulling the base board 43 upwardly along the guide rails 35 and the desired extended position of the base board 43 may be determined by positioning the board 43 with the flanges 47 engaging in slotted slots or grooves 48 in the lower side of the base board 43. In extending or moving the typewriter from the storage chamber 41 to operative position, the top 61 is raised to open position by initially swinging the front top section 63 to the position shown in Figure 3, and then raising the rear top section 62 to the position shown in Figure 6. Raising the top sections to the positions indicated will provide sufficient space for the passage of the typewriter mounted on the board 43.

Where it is desired to use a second instrument with the typewriter in the storage chamber 41, the front top section 63 may be raised to the position shown in Figure 3 as a copy holder, and the second instrument then placed on the horizontal wall or shelf 32.

The board 43, in its movement into or out of the storage chamber 41, is adapted at its opposite side edges, to engage against the inclined guide members 91 which are secured to the side panels 23 and against which the rails 35 are adapted to also be secured. The guide members 91 extend upwardly and forwardly to the rails 34, as shown in Figures 3 and 6, and also constitute a reinforcing for the panels 23. The rails or strips 49 are of sufficient height that when the base board 43 is in operative position over the wall 32 the rollers 50 will be raised out of contact with the wall 32, the rail 49 contacting the board 49 outwardly of the rollers 50.

The adjustment of the base board 43 with the typewriter or other instrument thereon permits the user to adjust himself relative to the copy or work on the copy holder so that the copy or work can be properly focused by the eyes of the user. The forward offsetting of the front portion of the desk eliminates the possibility of the user bumping the inclined bottom wall in either the open or closed position of the top, and also permits the user to either rise from, sit down or turn in a chair without pushing the chair rearwardly.

I claim:

1. A desk comprising a body formed of opposite side walls, a rear end wall, an inclined inner wall between said side walls and inclining downwardly and rearwardly, a horizontal forward wall secured between said side walls and also secured to the forward upper end of said inclined wall, an instrument base board slidable between said side walls and engageable with said inclined wall and said horizontal wall, said base board being provided with spaced apart aligned pairs of grooves in the lower face thereof, and a pair of upwardly extending aligned flanges carried by the upper side of said horizontal wall and engageable in selected grooves of said base board to hold the latter in lengthwise adjusted position.

2. A desk comprising a body formed of opposite side walls, a rear end wall, an inclined inner

wall between said side walls and inclining downwardly and rearwardly, a horizontal forward wall secured between said side walls and also secured to the forward upper end of said inclined wall, an instrument base board slidable between said side walls and engageable with said inclined wall and said horizontal wall, said base board being provided with spaced apart aligned pairs of grooves in the lower face thereof, a pair of upwardly extending aligned flanges carried by the upper side of said horizontal wall and engageable in selected grooves of said base board to hold the latter in lengthwise adjusted position, and confronting stop flanges carried by said side walls, said base board having cutouts in the opposite sides thereof forming shoulders engageable with said stop flanges to limit the forward extension of said base board over said horizontal wall.

3. A desk comprising a body formed of opposite side walls, a rear end wall, an inner inclined wall fixed between said side walls and also fixed at its rear lower end to said rear wall, said inclined wall constituting a guide, a horizontal upper wall extending from the upper end of said

25 inclined wall, aligned flanges secured to the upper side of said horizontal wall adjacent the forward edge thereof, a flat base board loosely disposed between said side walls and movable from a position upon said guide to a position upon said horizontal wall, said base board having a plurality of aligned pairs of grooves for receiving said flanges, a pair of downwardly and forwardly projecting stop members fixed to said side walls, and yieldable bumpers carried by said stop members.

35 4. A desk comprising a body formed of opposite side walls, a rear end wall, an inner inclined wall fixed between said side walls and also fixed at its rear lower end to said rear wall, said inclined wall constituting a guide, a horizontal upper wall extending from the upper end of said

40 inclined wall, aligned flanges secured to the upper side of said horizontal wall adjacent the forward edge thereof, a flat base board loosely disposed between said side walls and movable from a position upon said guide to a position upon said horizontal wall, said base board having a plurality of aligned pairs of grooves for receiving said flanges, a pair of downwardly and forwardly projecting stop members fixed to said side walls, said stop

45 members having cutouts confronting said guide with one side of each cutout parallel with and offset from said guide to thereby hold said base board against rearward tilting.

5. A desk comprising a body formed of opposite side walls, a rear end wall, an inner inclined wall fixed between said side walls and also fixed at its rear lower end to said rear wall, said inclined wall constituting a guide, a horizontal upper wall extending from the upper end of said

60 inclined wall, aligned flanges secured to the upper side of said horizontal wall adjacent the forward edge thereof, a flat base board loosely disposed between said side walls and movable from a position upon said guide to a position upon said horizontal wall, said base board having a plurality of aligned pairs of grooves for receiving said flanges, a pair of downwardly and forwardly projecting stop members fixed to said side walls, said stop members having cutouts confronting

65 said guide with one side of each cutout parallel with and offset from said guide to thereby hold said base board against rearward tilting, and yieldable bumpers carried by said stop members.

WILLIAM JAMES BARGEN.
